UNITED STATES PATENT OFFICE.

BYRON L. BACOT, OF McCOMB, MISSISSIPPI.

ROOFING-TILE.

No. 912,353.

Specification of Letters Patent.

Patented Feb. 16, 1909.

Application filed February 21, 1908. Serial No. 417,215.

To all whom it may concern:

Be it known that I, BYRON L. BACOT, a citizen of the United States, residing at McComb, in the county of Pike and State of Mississippi, have invented certain new and useful Improvements in Roofing-Tile, of which the following is a specification.

This invention relates to tile-roofs and has for its object to provide an improved tile together with improved means for fastening the same to the roof-timbers as will be described more fully hereinafter and pointed out in the claims.

In the accompanying drawing Figure 1 is a plan view of a portion of a roof laid with my tile, parts being shown in sections. Fig. 2 is a section on the line 2—2, Fig. 3 is a section on the line 3—3; and Fig. 4 is a section on the line 4—4 of Fig. 1. Fig. 5 is a bottom plan view of one of the tiles. Fig. 6 is a section on the line 6—6 of Fig. 2.

Referring specifically to the drawing, the tile 6 has a substantially rectangular outline with two diagonally opposite corners cut off and beveled as indicated at 7 and 8, respectively. The tile is corrugated or fluted to form ridges and depressions running from the top to the bottom of the tile. At the apex of the ridges on the bottom of the tile, near its lower edge, are lugs 9 which fit in notches 10 in the upper edge of the next tile below when the tiles are in position on the roof. By interlocking the tiles as stated lateral displacement is prevented. The lugs 9 are enlarged as indicated at 11 so that they may engage the upper side of the longitudinal roofing-strips 12. The upper side of the part 11 has a conoidal projection 13, and extending through the part 11 from the apex of said projection is a nail hole 14 to receive a nail 15 which is driven into the roofing-strip engaged by the lug, whereby the tile is securely fastened and held in position on the roof. At a point near the back of the tile the part 11 has a hole 16 which extends parallel to the nail-hole 14, and communicates therewith by means of a slot 17. The width of the slot is such that the shank of the nail 15 can pass therethrough, and the hole 16 is large enough to admit the head of the nail. This enables the nail to be bent up through the slot to bring its head in line with

the hole 16 after which the tile can be removed without pulling the nail out of the roofing-strip.

55

The object of the conoidal projection 13 is to enable the nail to be driven close up to its head without danger of striking the lug with the hammer. With a square faced lug the hammer would have to be kept perfectly 60 square with the lug, and upon driving the nail close up to its head, the hammer is apt to strike the lug and break it off, thus rendering the tile useless; or the nail would have to be only partly driven. In the present construction, if the hammer should strike the projection 13, it will only break off the point thereof as it is the weakest portion, and the tile would then still be serviceable. When the nail is bent up in the slot 16 it will project from that side of the part 13 sufficiently to permit it to be readily grasped for removal.

70

The thickness of the lug 9 is the same as that of the tile so that the overlapping top and bottom edges of the tiles will lie close 75 together, and the back of the tile next below will be in contact with the roofing-strip as clearly shown in Fig. 2. This arrangement makes a close joint between the tiles. The walls of the notches 10 are inclined, and 80 the abutting sides and end of the lugs 9 are shaped accordingly to closely fit the same. When in position on the roof, one of the longitudinal edges of a tile overlaps the longitudinal edge of the adjacent tile to the left, and 85 the bevel 8 abuts against the bevel 7 of the next tile below to the left. The joint between the bevels 7 and 8 is overlapped on the top and the bottom by the ends of the adjacent tiles of the two courses, and the depression of the lower overlapping tile is under 90 the joint as shown in Fig. 4. This arrangement completely incloses the joint, but if any water should get between the joint it will run into the depression just referred to and down. 95 the same onto the next tile below and so on off the roof.

The tile herein described is simple in construction and therefore can be cheaply produced. The fastening means securely hold 100 it in place, and by the arrangement of the joints and overlapping parts a smooth and rain-proof roof is had. The roof is also proof against damage from the wind as the

latter cannot get under the tiles. If the roof requires repairs any of the tiles can be readily removed without removing adjacent tiles.

I claim:

- 5 1. A roofing-tile having on one side a perforated lug the outer end of which is reduced to form a portion which is frangible to a greater degree than the main body of the lug.
2. A roofing-tile having on one side a lug

formed with a conoidal projection and having 10 a perforation extending through the lug from the apex of the projection.

In testimony whereof I affix my signature, in presence of two witnesses.

BYRON L. BACOT.
